UNITED STATES PATENT OFFICE.

WILLIAM SAGL, OF MINNEAPOLIS, MINNESOTA.

COIL-FORMING MACHINE.

Application filed September 14, 1921. Serial No. 500,554.

To all whom it may concern:

Be it known that I, WILLIAM SAGL, a citizen of the United States, residing at Minneapolis, in the county of Hennepin and State of Minnesota, have invented certain new and useful Improvements in Coil-Forming Machines, of which the following is a specification.

My invention relates to coil forming machines, and an object is to provide for winding and forming wire into elongated coils for use in dynamos and electric motors. A further object is to provide a machine of this character which may be readily adjusted for varying the size and shape of the coils. Another object is to provide a machine of this character in which the turns of wire when laid to form a coil will be disposed in such manner as to have inclined or angular arrangement.

The full objects and advantages of my invention will appear in connection with the detailed description, and the novel features embodied in my inventive idea will be particularly pointed out in the claims.

In the accompanying drawings which illustrate one embodiment of my invention, Fig. 1 is a top plan view. Fig. 2 is a view in side elevation with a small portion in section. Fig. 3 is a view in vertical section on the line 3—3 of Fig. 1. Fig. 4 is a view in vertical section on the line 4—4 of Fig. 1. Fig. 5 is a view in vertical section on the line 5—5 of Fig. 1. Fig. 6 is a fragmentary view on the line 6—6 of Fig. 1. Fig. 7 is a view in longitudinal section showing the manner of winding the wire to form a coil. Fig. 8 is a plan view of the coil after it has been wound but before it has been opened up. Fig. 9 is a plan view of the coil after it has been opened up into finished condition.

Referring to the construction shown in the drawings, the numeral 10 designates in general the frame of the machine at the upper end of which is an extended support 12 to which is fastened an electric motor 14 and a casting 16 in which is embodied a gear casing 18. A worm 20 is secured to the extended shaft 22 of the motor 14 and this worm meshes with a worm gear 24 in the gear casing, and this worm gear is secured to a shaft 26 having bearings in the opposite sides of the gear casing. Secured to one end of the shaft 26 is a head 28 to which are fastened upper and lower rods 30

and 32 which extend at both sides of the head in parallel relation to each other. Two jaws 34 and 36 are slidably mounted on the rod 30, one on each side of the head 28. These jaws are provided with inclined grooves 37 for receiving the wire when it is laid to form a coil. Rotatably mounted in a collar 38 secured to the head 28 is a rod 40 having opposite end portions 42 and 44 which are threaded right and left hand to engage corresponding threads in threaded openings in the jaws 34 and 36. The rod 40 is provided with a squared end 46 by means of which it may be turned to adjust the jaws 34 and 36 toward and away from each other. Rotatably mounted in a collar 48 is a rod 50 having opposite end portions 52 and 54 which are threaded right and left hand to engage corresponding threads in threaded openings 75 in jaws 56 and 58 which have inclined grooves 59 in which the wire is placed when the coil is being formed. The rod 50 is provided with a squared end 60 by means of which these latter jaws may be adjusted toward and away from each other. In order that these jaws may be moved in this manner, they are provided with dovetailed recesses which receive dovetailed projections 62 formed on the lower edge of a barlike member 64 carried by the collar 48. The member 64 is mounted for transverse movement upon a pair of rods 66 and 68, the inner ends of which are threaded into lugs on the head 28 as best shown in Fig. 5. 90 Slidably mounted upon the opposite ends of the rods 30 and 32 are supports 70 and 72 which contain openings provided with right and left hand threads which are engaged by corresponding threads upon the opposite portions of a shaft 74. The ends of the rods 30 and 32 are connected by plates 76 and 78 which are provided with bearings for the shaft 74. Adjustable stops 80 and 82 are held in desired position upon the rod 30 by 100 means of set screws, and these stops serve to limit the outward position of the supports 70 and 72. For rotating the shaft 74 at the proper time, I mount a small electric motor 84 upon a bracket 86 adjacent one end 105 of the shaft. The shaft of this motor is provided with a gear 88 which meshes with a gear 90 secured to the shaft 74. When it is desired to rotate this shaft and shift the supports 70 and 72 suitable wires are connected to the motor for supplying electricity thereto. A bolt 92 is screwed at one end into

the support 70 and mounted on this bolt is a wire receiving member having a corrugated cylindrical surface 94 terminating in a conical surface 96 which is terminated by a grooved member 98. A bolt 100 is similarly screwed into the support 72 and mounted on this bolt is a wire receiving member having a corrugated cylindrical surface 102 terminating in a conical surface 104. Referring to Fig. 2, the numeral 106 designates a leading-in wire for conducting electric current to a movable switch member 108 adapted to be moved into contact with a post 110 to which is connected a wire 112 leading to a contact member 114 attached to the core 116 of a solenoid having a coil 118. The contact member 114 is normally held in contact with one terminal of a wire 120, this wire being connected with the motor 14 for supplying current thereto and a return wire 122 being attached to the motor. When it is desired to stop the motor, the switch member 108 is moved into contact with a post 124 which is connected by a wire 126 with one terminal of the solenoid coil 118, the other terminal thereof being connected by a wire 128 with a coil 130 of one member of an electric brake. This coil is connected by a wire 132 with the return wire 122. The coil 130 surrounds the shaft 26 and when energized attracts a slidable member 134 having a friction disc 136 secured thereto and containing a disc 138 keyed to the shaft 26 so that when the discs engage, the rotation of the shaft 26 is quickly stopped.

The operation and advantages of my invention will be readily understood from the foregoing description. Wire for forming the coil is drawn from a reel or suitable supply of wire and the free end of this wire designated at W is attached to a hook member 140 adapted for engagement with the grooved member 98. Upon starting the motor 14, the wire will be laid into the grooves 37 of the jaws 34 and 36 and into the grooves 59 of the jaws 56 and 58 as shown in Fig. 5 and will pass around the wire receiving members as shown in Fig. 4. When the desired quantity of wire has thus been formed into a coil, the switch 108 is moved to bring it in contact with the post 124 and the rotation of the shaft 26 carrying the head 28 and the rods 30 and 32 is stopped. The coil C will then appear in plan as shown in Fig. 8. The operator then starts the motor 84 so as to somewhat retract the wire receiving members and stops the motor when these members have been caused to move toward each other the proper amount. The operator then grasps the jaws 56 and 58 or parts associated therewith and causes them to be pulled outwardly into the position indicated in dotted lines in Fig. 5. This causes the coil to assume the opened-up condition shown in Fig. 9 with

the portions A and B having an angular relationship to the end portions of the coil. It is obvious that the size and shape of the coil may be readily varied by turning the screw-threaded rods 40 and 50 to adjust the positions of the two pairs of jaws and by operating the motor 84 to bring the wire receiving members closer to or further from the head 28. Both pairs of jaws are readily removable and may be replaced by other pairs of jaws to still further vary the size of the coil. The use of my machine results in the production of a very rigid coil which fits better and remains more securely in place than would otherwise be the case. It also results in a saving of wire. The motor 84 may be rotated in either direction according to the manner in which the supply wires are connected thereto.

I claim:

1. A coil forming machine comprising two sets of spaced jaws having inclined recesses, wire receiving members positioned beyond said jaws at both sides thereof and having inclined surfaces, said recesses and said surfaces being adapted to receive wire as it is laid to form a coil, and means whereby one set of jaws may be moved relatively to the other set to open out the coil after the same has been laid. 85

2. A coil forming machine comprising two sets of spaced jaws having inclined recesses, means for adjusting the distance between the jaws of each set, wire receiving members positioned beyond said jaws at both sides thereof and having inclined surfaces, means for adjusting the distance between said members, said recesses and said surfaces being adapted to receive wire as it is laid to form a coil, and means whereby one set of jaws may be moved relatively to the other set to open out the coil after the same has been laid. 95

3. A coil forming machine comprising a frame, a shaft rotatably mounted on said frame, an electric motor for driving said shaft, a head secured to said shaft, two sets of spaced jaws carried by said head, extensions carried by said head, wire receiving members mounted on said extensions, means whereby one set of jaws may be moved relatively to the other set to open out the coil after the same has been laid, an electric brake for stopping the rotation of said head and permitting movement of the jaws, and means for simultaneously cutting off the supply of current to said motor and for causing said brake to operate. 110

4. A coil forming machine comprising a frame, a shaft rotatably mounted on said frame, a head secured to said shaft, two sets of spaced jaws carried by said head, extensions carried by said head, supports slidably mounted on said extensions, wire receiving members mounted on said supports, a motor 125

adapted to move said supports both toward and away from each other, and means whereby one set of jaws may be moved relatively to the other set to open out the coil after it has been laid.

5. A coil forming machine comprising a frame, a shaft rotatably mounted on said frame, an electric motor for driving said shaft, a head secured to said shaft, two sets 10 of spaced jaws carried by said head, extensions carried by said head, supports slidably mounted on said extensions, wire receiving members mounted on said supports, a motor adapted to retract said supports, 15 means whereby one set of jaws may be moved relatively to the other set to open out said coil after the same has been laid and after said supports have been retracted, and a brake for stopping rotation of said 20 head when the supply of current to said first mentioned motor is cut off.

6. A coil forming machine comprising a frame, a shaft rotatably mounted on said

frame, a head secured to said shaft, two sets of spaced jaws carried by said head, 25 said jaws having inclined recesses, two parallel rods secured to said head, supports slidably mounted on the opposite end portions of said rods, a shaft having its opposite end portions threaded right and left 30 hand and engaging corresponding threaded openings in said supports, means for rotating said threaded shaft in either direction, wire receiving members mounted on said supports, said members having cylindrical surfaces 35 terminating in conical surfaces, said recesses and said surfaces being adapted to receive wire as it is laid to form a coil, and a pair of transverse rods secured to said head, one set of jaws being slidably mounted 40 upon said rods whereby the coil may be opened out after it has been laid.

In testimony whereof I hereunto affix my signature.

WILLIAM SAGL.
